UNITED STATES PATENT OFFICE.

GEORGE H. CLIFF, OF PHILADELPHIA, PENNSYLVANIA, ASSIGNOR TO THE DELONG HOOK AND EYE COMPANY, A CORPORATION OF WEST VIRGINIA.

DESIGN FOR AN EYE FOR GARMENT-FASTENERS.

SPECIFICATION forming part of Design No. 35,639, dated January 28, 1902.

Application filed December 18, 1901. Serial No. 86,451. Term of patent 14 years.

To all whom it may concern:

Be it known that I, GEORGE H. CLIFF, a citizen of the United States, residing in the city and county of Philadelphia, State of Pennsylvania, have invented and produced a new and original Design for an Eye for a Garment-Fastener, of which the following is a specification, reference being had to the accompanying drawings, forming part thereof.

10 The leading feature of my design for an eye for a garment-fastener is a cross-bar with legs on the ends thereof and loops extending outwardly from said legs, said loops being of quadrangular form.

15 Figure 1 represents a perspective view of an eye for a garment-fastener embodying my design. Fig. 2 represents a top or plan view thereof.

In the drawings, A designates an eye for a garment-fastener, the same consisting of the 20 cross-bar B, the legs C on the ends thereof, and the loops D, which extend outwardly from the bases of said legs, said loops being of quadrangular form and having two long sides E and two short sides F.

25 Having thus described my invention, what I claim as new, and desire to secure by Letters Patent, is—

The design for an eye for a garment-fastener, substantially as shown and described. 30

GEORGE H. CLIFF.
